His Attorney.

UNITED STATES PATENT OFFICE

WALTER R. G. BAKER, OF SCHENECTADY, NEW YORK, ASSIGNOR TO GENERAL ELECTRIC COMPANY, A CORPORATION OF NEW YORK

SIGNALING SYSTEM

Application filed November 6, 1923. Serial No. 673,191.

My present invention relates to signaling systems and more particularly to systems in which high frequency signaling currents are transmitted over high potential electrical transmission lines.

In systems of the type here involved it has been proposed to impress the high frequency signaling currents upon the power conductors by suspending a coupling wire 10 parallel to the power conductors and between the power conductors and earth. With this arrangement the capacity between the coupling wire and earth is large enough in comparison with the capacity between the coupling wire and the transmission conductors to cause a considerable energy loss and an appreciable radiation of high frequency waves which is undesirable. I have discovered that this difficulty may be largely 20 overcome by so locating the coupling wire that it is surrounded by the transmission conductors. It will then be shielded to such an extent that most of the high frequency energy will be transferred to the transmission conductors and there will be little radiation.

In carrying my invention into effect the coupling wire may preferably be located symmetrically with respect to the transmission conductors. In the case of a single three-phase transmission line, for example, the coupling wire should be located at equal distances from all three of the transmission conductors. When arranged in this way the capacity between the coupling wire and earth 30 will also be less than when the coupling wire is beneath the line conductors. The potentials induced in the coupling wire from the transmission conductors will also in this case be substantially neutralized.

40 My invention will best be understood by reference to the following description taken in connection with the accompanying drawing in which I have indicated diagrammatically one way in which my invention may be carried into effect.

I have indicated in the drawing a transmission system comprising two three-phase transmission lines made up of conductors 1 to 6, inclusive. The transmission conductors are supported by towers of conventional

form of which only two, 7 and 8 are indicated. The coupling wire 9, which is enclosed within a space bounded by the transmission conductors, is suspended between the towers 7 and 8, and insulated therefrom by strain insulators 10. A lead 11 connects the coupling wire 9 with earth and a signaling apparatus 12 is connected to the earth lead 11 by the usual coupling transformer 13.

It will be noted that the coupling wire is surrounded by the transmission conductors, being located entirely within the space enclosed by planes passing through adjacent conductors on the four sides of the coupling wire. It is also symmetrically located with respect to the transmission conductors, being equidistant from conductors 1, 3, 4, and 6, and from conductors 2 and 5. The arrangement described may be used either for transmission or reception; that is, the apparatus 12 may be either a transmitting or a receiving apparatus.

While I have shown and described only one embodiment of my invention, it will be apparent that many modifications of my invention may be made without departing from the scope thereof as set forth in the appended claims.

What I claim as new and desire to secure by Letters Patent of the United States, is:

1. The combination in a high frequency transmitting system of a high potential electrical transmission line comprising three or more conductors supported above the earth, a coupling conductor extending parallel to the conductors of said transmission line and symmetrically arranged with respect thereto, a high frequency apparatus for energizing said coupling conductor and a connection between said coupling conductor and said high frequency apparatus.

2. The combination in a high frequency transmitting system of a high potential electrical transmission line supported above the earth, said transmission line comprising more than two conductors arranged in intersecting planes, a coupling conductor extending parallel to the conductors of said transmission line and located entirely within a space enclosed by planes passing through adjacent

- conductors, high frequency apparatus for energizing said coupling conductor and a connection between said coupling wire and said high frequency apparatus.
3. The combination in a high frequency transmitting system of an electric transmission line supported above the earth and comprising a plurality of electrical conductors arranged to enclose a substantially rectangular space, a coupling conductor extending parallel to the conductors of said transmission line and located within the space enclosed by said conductors, high frequency apparatus for energizing said coupling conductor and a connection between said coupling conductor and said high frequency apparatus.
4. The combination in a high frequency transmitting system of an electrical transmission line supported above the earth, said transmission line comprising more than two conductors arranged in intersecting planes, a coupling conductor extending parallel to the conductors of said transmission line and disposed within a space bounded by the conductors of the transmission system, high frequency apparatus for energizing said coupling conductor and a connection between said coupling conductor and said high frequency apparatus.
5. The combination in a high frequency transmitting system of an electric transmission line comprising a plurality of conductors supported above the earth, a coupling conductor extending parallel to the conductors of said transmission lines, certain of the conductors of the transmission lines being disposed between the coupling conductor and the earth and in such proximity to said coupling conductor and to each other that there is little or no radiation between the coupling conductor and the earth, high frequency apparatus for energizing said coupling conductor and a connection between said high frequency apparatus and said coupling conductor.

45 In witness whereof, I have hereunto set my hand this 5th day of November, 1923.

WALTER R. G. BAKER.
